UNITED STATES PATENT OFFICE.

DAVID TOWNSEND SHARPLES, OF WESTCHESTER, PENNSYLVANIA.

FEED-REGULATING MECHANISM FOR LIQUIDS.

SPECIFICATION forming part of Letters Patent No. 699,249, dated May 6, 1902.

Application filed August 6, 1901. Serial No. 71,045. (No model.)

To all whom it may concern:

Be it known that I, DAVID TOWNSEND SHARPLES, a citizen of the United States of America, and a resident of Westchester, in 5 the county of Chester and State of Pennsylvania, have invented certain new and useful Improvements in Feed-Regulating Mechanism for Liquids, of which the following is a specification.

10 My invention relates to an improved feed mechanism for liquids designed to maintain a uniform flow under varying pressures in the source of supply. To attain this result, I provide for dividing the stream of liquid 15 from the reservoir, so that one portion will be delivered directly into the discharge-outlet and another limited portion will be indirectly delivered thereto and intermediately utilized to automatically vary the size of the 20 direct outlet, so that the two portions jointly will furnish a uniform discharge under varying conditions.

The invention is fully described in connection with the accompanying drawing and the 25 novel features are particularly pointed out in the claims.

The drawing is a sectional elevation of an apparatus embodying the essential features of my invention in simple form.

30 A represents what may be termed the "faucet-body," which, as shown, is provided with a hollow stem *a*, adapted to be connected to a source of liquid-supply, as tank *B*, (partially indicated in dotted lines,) and to 35 serve as a passage-way, which may be controlled by a stop-cock *b*, into a chamber *c*. This chamber *c* is provided with a discharge-outlet into a vertical tube *d*, forming a discharge-nozzle, which may be fitted, if desired, 40 with a regulating-cock, (not shown,) and it is also provided with an overflow outlet or outlets leading into an overflow-chamber *E* above it. This overflow-outlet is preferably formed by a circular opening *e*, arranged in line with 45 the discharge-outlet tube *d* and adapted to serve also as a loose guideway for the depending tubular neck *f* of a float-cup *F*, located in the overflow-chamber *E*. This float may be of any desired form, having an opening or openings 50 in the top portion thereof to permit inflow of liquid from the overflow-chamber *E*, as hereinafter described, and its tubular

neck, which rises and falls with the float-cup, is adapted when in normal position to seat around the discharge-outlet from the discharge-chamber *c*, so as to cut off the direct flow from said chamber through the discharge-nozzle; but the opening *e* being somewhat larger in diameter than the tubular neck *f* passing therethrough provides a restricted annular overflow-outlet from the chamber *c* into the overflow-chamber *E*. The tubular neck *f* when unduly raised from its seat also serves as an overflow-outlet from the chamber *c* into the float-cup *F*, as herein-after described.

The operation of the mechanism is as follows: When the stop *b* is opened, the liquid flows into the chamber *c*. Being cut off from the discharge-tube *d* by the lowered float-cup *F*, the neck *f* rises through the overflow-outlet *e* into the overflow-chamber *E* and gradually fills the latter until the empty float-cup *F* rises and opens the discharge-outlet, so as to permit a direct discharge into the tube *d*. 75 When the float-cup *F* is raised by the overflow into chamber *E*, so far as to admit a greater supply of liquid between the base of its tubular neck and the outlet *d* than the latter is able to discharge, the surplus will 80 overflow direct into the tubular neck and upward into the float-cup itself until the latter is so weighted by this overflow surplus as to lower it and thereby automatically reduce the valve-opening and the inflow from the chamber *c* to the outlet *d*. Thus the restricted overflow through outlet *e* into the chamber *E* tends to raise the float-cup *F* and open the valve formed by its tubular neck, while the surplus overflow through the latter into the 85 float-cup tends to lower the latter until this surplus is stopped. The constant overflow into chamber *E* constantly tends to raise the float-cup and valve higher than is necessary to fully supply the discharge-outlet *d*, thus 90 providing a surplus which overflows into the float-cup and holds the latter down notwithstanding the constant overflow into chamber *E* tending to raise the liquid-level in the latter, which level, however, is controlled by the 95 communication provided through the openings *g* with the float-cup, through which the overflow from the opening *e* is thus indirectly delivered to the discharge-outlet *d*, together 100

with just a sufficient amount supplied directly to the latter by the proper automatic opening of the float-valve. Supposing, for instance, that the liquid in tank B is suddenly increased 5 to twice the height, the effect of the increased head would be to somewhat increase the overflow at *e* and to cause a rapid surplus overflow through the tubular neck *f* into the float *F*, the outlet *d* being unable to discharge it. 10 The immediate result would be that the float *F* would sink and cut off the valve opening to *d*, the overflow into chamber *E* at the same time causing a top flow into the float *F*. The supply to the discharge-outlet *d* is thus made 15 up of the overflow through *e* plus the supplementary amount needed to fill said outlet *d* and which is admitted directly from the chamber *c* through the automatically-adjusted opening of the float-valve formed by the neck 20 *f*. In practice the flow capacity through the stem *a* should always be somewhat greater than the discharge capacity of the nozzle, so as to provide an overflow at all times through the outlet *e*, while the surplus overflow 25 through *f* to the float would be a temporary one, quickly effecting a corresponding reduction of the valve-opening. The outlet or outlets *e* are of proper size to restrict the overflow therethrough, preventing possible overfilling of the chamber *E* and requiring always 30 a partial raising of the float to fully supply the nozzle.

The particular construction shown and described may obviously be considerably modified without departing from the spirit of my invention.

What I claim is—

1. A feed-regulating mechanism for liquids comprising a chamber having a supply-inlet a 40 discharge-outlet pipe and an overflow-outlet, and a movable device operated by the overflow from said chamber to vary the communication between the chamber and the discharge-outlet and serving to conduct the overflow indirectly to the latter.
2. A feed-regulating mechanism for liquids comprising a chamber having a supply-inlet a 45 discharge-outlet pipe and a direct-overflow

outlet of less capacity than said discharge-outlet, and a movable conductor for said direct-overflow liquid to said discharge-outlet forming an automatically-operated valve adapted to regulate direct communication between the latter and said chamber.

3. In a feed-regulating mechanism for liquids having a main chamber with a supply-inlet, a discharge-outlet, and an overflow-outlet, and overflow-receiving chamber and a float-cup in said overflow-chamber arranged to automatically regulate direct communication between said discharge-outlet and the main chamber.

4. In a feed-regulating mechanism for liquids having a main chamber with a supply-inlet, a discharge-outlet, and an overflow-outlet, an overflow-receiving chamber and a float-cup in said overflow-chamber communicating with said discharge-outlet and arranged to automatically regulate the direct discharge from said main chamber.

5. In a feed-regulating mechanism for liquids having a main chamber with a supply-inlet, a discharge-outlet, and an overflow-outlet, an overflow-receiving chamber and a float-cup in said overflow-chamber having a 75 tubular depending neck entering said chamber and adapted to seat upon said discharge-outlet to cut off the latter from direct communication with the main chamber.

6. In a feed-regulating mechanism for liquids having a main chamber with a supply-inlet, a discharge-outlet, and an overflow-outlet, an overflow-receiving chamber and a float-cup in said overflow-chamber having a 80 tubular depending neck passing loosely through said overflow-outlet into the main chamber and adapted to seat upon said discharge-outlet to cut off the latter from direct communication with the main chamber.

Signed at Westchester, Pennsylvania, this 90
26th day of July, 1901.

DAVID TOWNSEND SHARPLES.
